UNITED STATES PATENT OFFICE.

WILLIAM E. OAKLEY, OF MILLBURY, MASSACHUSETTS, ASSIGNOR TO WORCESTER STEEL FOUNDRY COMPANY, OF WORCESTER, MASSACHUSETTS, A CORPORATION OF MASSACHUSETTS.

RAIL-BOND FOR ELECTRIC RAILWAYS.

No. 895,582.

Specification of Letters Patent.

Patented Aug. 11, 1908.

Application filed December 2, 1904. Serial No. 235,195.

To all whom it may concern:

Be it known that I, WILLIAM E. OAKLEY, a citizen of the United States, residing at Millbury, in the county of Worcester and 5 Commonwealth of Massachusetts, have invented a new and useful Improvement in Rail-Bonds for Electric Railways, of which the following is a specification, accompanied by drawings forming a part of the same, in 10 which—

Figure 1 is a perspective view of the adjoining ends of two rails of an electric railway, connected by a rail bond constructed according to my improved method. Fig. 2 15 is a perspective view of one of the terminals of my improved rail bond. Fig. 3 is a central sectional view of one of the terminals of a rail bond constructed according to my improved method and applied to a rail. Fig. 4 20 is a sectional view of a founder's flask containing a matrix for a rail bond terminal constructed according to my improved method, and Fig. 5 is a plan view of the lower portion of a founder's flask showing one half 25 of the matrix for casting the terminal with one end of the flexible connection placed in position to be embedded therein.

Similar reference letters and figures refer to similar parts in the different views.

30 My invention consists in an improvement upon the method of making rail bonds described in my application, Serial No. 156,874, filed May 13, 1903. In that application I have described a method of making rail bonds in which the metal of the terminal possessed a temperature coefficient similar to that of the metal of the rail, and where the ends of the flexible connection between the terminals were inserted in the matrix of the 35 terminal mold. The molten steel or like metal for the terminal was delivered with a considerable force and at an extremely high temperature upon the ends of the flexible connection of copper or like metal with low 40 electrical resistance, from which resulted both a fusion of the copper connection and also a considerable mechanical agitation of the particles of copper and a mixture of them through the metal of the terminal. This formed 45 a terminal which possessed the good qualities of both metals without the disadvantages attending the use of either metal alone,

to wit, either increased resistance, if the terminal were made entirely of steel, or a difference in expansion and contraction if the 55 terminal were entirely of copper, which soon destroyed the union of the terminal and the rail and reduced the electrical conductivity of the bond.

The method pointed out in my pending application, Serial No. 156,874, largely decreased the electrical resistance of the terminal because of the intermingled copper, and also, because largely composed of steel, the terminal formed a perfect joint with the rail, 65 which does not deteriorate by expansion or contraction or other influences incident to a terminal made entirely of copper. As the intermingling of the copper and the steel was due entirely to the impact of the molten steel 70 upon the end of the copper cable, it is a matter which can not be accurately determined and an even distribution of the copper through the steel obviously does not occur. In order also to facilitate proper melting and 75 mingling of the connector by the impact of the molten steel, I preferably constructed the connector of a number of small wires twisted together forming a cable instead of one solid wire. The portion of the cable entering the 80 terminal which was not melted formed a less perfectly welded joint than the surface of a solid cable, and the heat necessary to fuse the twisted cable had tended to disintegrate or burn that portion of the cable immediately 85 adjacent to the melted portion.

Referring to the accompanying drawings 1, 1, denote portions of two adjacent rails of an electric railway, 2 is a flexible connection and 3, 3, are the terminals of a rail bond uniting the rails 1, 1, and constructed according 90 to my improved method. The connector 2 may be of any desired construction, in the present instance consisting of a single copper wire. The terminal 3 cast as hereafter described, is provided on one side with a cylindrical extension 4 having its outer surface slightly tapered from a shoulder 5 toward its end. The end of the extension 4 is provided with a shallow recess 6, preferably with 95 tapering sides, making the recess in the form of a frustum of a cone surrounded with a narrow annular rim 7 arranged to project slightly through the web 8 of the rail. The 100

taper of the surface is preferably about one sixtieth of an inch and the terminal is applied to the rail by forming a round hole 9 in the web 8 of the rail substantially of the same 5 diameter as that of the smaller end of the extension 4. The extension 4 is then driven or pressed into the hole 9 forming a tight fit and the rim 7 is upset, thereby expanding the recessed end and holding the terminal 10 securely in place.

By my improved method the terminal 3 is cast in a suitably shaped matrix 10 conveniently formed in founder's sand in a flask 11 with a suitable channel 12 for the admission 15 of the molten metal, the composition of which will hereafter be described. The connector 2, consisting of a cable or preferably a wire of copper or other metal having a similar low electrical resistance, is inserted in the 20 flask with its end 13 projecting into the matrix 10 so as to be surrounded by the molten metal of the terminal 3. The terminal is cast from an alloy of metal consisting of steel or other metal having a temperature coefficient 25 approximating that of the rail, mixed with copper or other metal which possesses a similar low degree of resistance to an electric current. This mixture is made before the terminal is cast and the metals composing it 30 can be united in any desired proportion, and care can be exercised to obtain a thorough mixture. Of course any metal besides copper, having the necessary quality, to wit, low resistance, may be used to form this alloy 35 and I am not restricted to the metal of the flexible connector. After this alloy is formed the terminal is cast at a welding heat around the connector 2 which is thereby united to it, but which retains its shape and position in 40 the center of the terminal. As the end 13 is not to be melted, but simply a welded joint is required between the surface of the connector and the metal of the terminal, a very much smaller degree of heat in the metal of the terminal 45 may be employed so that the integrity of the copper wire is substantially undisturbed and the deteriorating effect of the excessive heat required to melt the end of the connector is avoided. I am also enabled to 50 use a solid wire connector between the terminals instead of a cable of twisted wires, thereby obtaining a better welding surface and more secure joint between the connector and the terminal than has been heretofore 55 possible.

A terminal constructed according to my improved method has then a center consisting of a solid wire or cable of copper or other metal of low resistance welded to a surrounding terminal composed of an alloy of a metal 60 having a similar temperature coefficient as the rail and a metal of low electrical resistance, not necessarily, however, the same as the metal of the connector. The composition 65 and uniting of this alloy can be conven-

iently accomplished in a crucible and is wholly under control, and it may be cast at a temperature but slightly above the welding heat of the metal of the connector. A solid wire may be used for the connector to which 70 the terminal may be firmly welded without any deterioration of the metal of the connector. By this method I am also enabled to alloy the terminal with any desired proportion of metal of a low resistance, and to 75 secure a more intimate and uniform commingling of the metals without material change in the temperature coefficient of the terminal. I find that the electrical conductivity of a bond prepared according to my 80 improved method is much increased, while its durability and electrical conductivity under expansion and contraction and other disturbing causes remains unaffected.

The electrical connection between the terminal and the connector is of course perfect being formed by a welding joint, and after the terminal is cast about the end of the connector, the bond is then completed by turning or milling the exterior surface of the extension.

What I claim as my invention and desire to secure by Letters Patent is:—

1. A rail bond for electric railways, comprising a connector and a pair of terminals, 95 welded to said connector, and composed of an alloy, formed before said welding, comprising a metal having a temperature coefficient substantially the same as that of the rail, and a metal having a low electrical resistance. 100

2. A rail bond for electric railways, comprising a connector and a pair of terminals welded to said connector, and composed of an alloy comprising a metal having a temperature coefficient substantially the same as that of the rail, and a metal having a low 105 electrical resistance, said metals being mixed to form said alloy in predetermined proportions.

3. A rail bond for electric railways, comprising a connector and a pair of terminals, said terminals held in electrical contact with the surface of said connector and composed of an alloy comprising, in predetermined 115 proportions, a metal having a temperature coefficient substantially the same as that of the rail, and a metal having a low electrical resistance.

4. As an article of manufacture, a rail bond for uniting the rails of an electric railway, and consisting of a connector and a pair of terminals, said connector having a low electrical resistance and said terminals being cast and composed of two metals, 120 thoroughly mixed before casting, one of said metals having a normal temperature coefficient approximating that of the rail, and the other of said metals having a low electrical 125 resistance. 130

5. A rail bond for electric railways, comprising a connector and a pair of terminals in electrical contact, said connector composed of a metal having a low electrical resistance and said terminals composed of an alloy formed before the contact of said connector and said terminals, and comprising a metal having a temperature coefficient substantially the same as that of the rail and a metal having a low electrical resistance.
